T. G. LOUIS

MAGNETO

Filed Sept. 3, 1926

UNITED STATES PATENT OFFICE.

TERRENCE G. LOUIS, OF SPRINGFIELD, MASSACHUSETTS, ASSIGNOR TO WICO ELECTRIC COMPANY, OF WEST SPRINGFIELD, MASSACHUSETTS, A CORPORATION OF MASSACHUSETTS.

MAGNETO.

Application filed September 3, 1926. Serial No. 133,493.

This invention relates to magnetos and is particularly directed to improvements in the mechanism for actuating the armature of a magneto.

The invention has to do primarily with magnetos of the so-called reciprocating armature type, wherein an armature is periodically moved toward and away from magnetic poles to vary the reluctance of a magnetic circuit. Usually and preferably, the armature, when moved toward said poles, is also brought into contact therewith. It has been customary heretofore to move the armature toward and into contact with its poles by the expansive effort of a return spring, which acts to accomplish this purpose as and when permitted by the mechanism used to unseat the armature from its poles and drive it way from the latter. Such mechanism, for magnetos which are driven at high engine speeds, may consist simply of a cam or any other means for effecting an inelastic transmission of force from the drive shaft of the magneto to the armature. However, it is usual, even in such magnetos to supplement such drive by a spring drive which may be optionally used on starting or at low engine speeds. The spring drive is always used for magnetos, which are driven at low engine speeds. In the spring drive a spring, initially insufficiently stressed to overpower the force of magnetic attraction tending to hold the armature to its poles, is periodically placed under stress, and allowed to act on the armature to move it away from its poles. Usually, this spring, even when fully stressed, is insufficient to overpower the magnetic hold on the armature and comes into play only after such hold has been broken by an inelastic transmission of force from the drive shaft, after which the spring expands and moves the armature at a speed independent of engine speed. The magneto is arranged to produce a spark during the flight of the armature away from its poles and up to the time of the production of the spark (when the breaker points open) it is desired to move the armature as rapidly as possible.

This invention is directed to, and has for one object, the elimination of the opposing force of the return spring during the initial stage of the flight of the armature away from its poles.

One way of accomplishing this object is to arrange the return spring so that it is effective to return the armature only part way toward its poles, but nevertheless sufficiently close thereto so that the remainder of the return flight can be effected by magnetic attraction.

Another object of the invention is to provide an arrangement whereby the spring, which customarily serves to yieldingly hold the breaker points of the interrupter closed, may be utilized for the additional function of moving the armature in the initial stage of its return flight and whereby the breaker points themselves may serve by their engagement as positive stops to prevent the spring from opposing the armature driving force during the initial stage of its flight away from the poles.

According to the last named object, there is an advantage due to the elimination of parts by making certain parts perform two functions and there is also the advantage of perfect coordination in timing because the return spring cannot oppose the downward movement of the armature until the breaker points open at which time the active part of the downward movement of the armature (that part effective to produce the spark) has been completed.

Other objects and features of the invention will appear in the following description and will be pointed out in the appended claims.

The invention will be disclosed with reference to the accompanying drawings, in which:

Fig. 1 is a front elevational view of a magneto embodying the invention;

Fig. 2 is a sectional plan view taken on the line 2—2 of Fig. 1, showing the armature driving mechanism as arranged for spring drive;

Fig. 3 is a fragmentary view, taken similarly to Fig. 2 but drawn to a larger scale and showing the armature driving mechanism as arranged for direct or inelastic drive;

Fig. 4 is a cross-sectional view taken on the line 4—4 of Fig. 1 but drawn to a larger scale to clearly show the armature driving mechanism; and

Fig. 5 is a cross-sectional view, taken on the line 5—5 of Fig. 1 but drawn to a larger

scale, illustrating the armature return spring and the means for preventing it from opposing the armature in the initial stage of its flight away from its poles.

5 The present invention, being primarily directed to improvements in the mechanism for operating the armature, is largely independent of the particular details of construction of the magneto proper. The magneto 10 shown is illustrative of a general type and is but one example of many and various magnetos of this general type with which the invention may be used.

15 The magneto, illustrated herein, includes a frame A of non-magnetic material, supported from and above a base B by supports legs L. Clamped to frame A by screws 6 and a bar 7 of non-magnetic material are a pair of laminated soft iron cores 8 which 20 extend vertically upward in spaced parallel relation and, near their upper ends, are recessed to receive a bank of permanent magnets 9 by which the cores are magnetically connected at their upper ends. A cross bar 25 10, of non-magnetic material, serves to tie the cores together.

25 Mounted on the cores 8 and located between this bar and frame A are primary coils 11. Encompassing each coil 11 is a 30 secondary coil 12. The coils 12 constitute the generating winding of the magneto and may be connected in any suitable and usual manner (not shown). The coils 11 are suitably connected, as for example in series, as 35 by a wire 13 and one terminal of the primary winding, comprised by the connected coils 11, is connected to the frame of the machine, as by a wire 14. The other terminal of the primary winding is connected as 40 by a wire 15, to a fixed but adjustable breaker point 16, mounted in the upper end of a tubular metallic casing 17 and insulated therefrom. Casing 17 is fixed in the bar 7 in vertically upstanding relation and serves 45 as a guide for a plunger 18, which carries the movable breaker point 19 of the interrupter mechanism. Plunger 18 has a vertically depending stem 20.

50 The armature 21 is made up of soft iron laminations which are clamped together by screws 22. Each screw 22 passes freely through a spacing sleeve 23 and one arm of a split piece 24 and is threaded into the other arm thereof. The split pieces 24 are 55 clamped by screws 22 to a shaft 25 which is mounted to turn in bearings in frame A. The screws 22 also serve to clamp to armature 21 a plate having a horizontally disposed ledge 26 through which the breaker point stem 20 freely passes. The armature 21, when positioned as shown in Fig. 5, contacts with and magnetically connects the lower ends of cores 8. It is adapted to be moved away from its poles by suitable mechanism to be later described and by its down-

ward flight to produce a change in flux in the magnetic circuit. At an intermediate point in the downward flight of the armature, the ledge 26 engages a flange 27 fixed to stem 20 and separates the breaker points 70 16 and 19. Thereby the circuit of the primary winding is broken in the usual manner and electromotive force is generated in the secondary coils 12.

75 The magneto, as thus far described, is of well known construction and, for the purposes of this invention, merely serves as a representative example of one magneto of a given type with which the invention may be used. The details of construction, as described, are therefore not important and may be varied in many and various ways.

80 According to the present invention the usual armature return spring has been eliminated and the location of the usual breaker point spring has been changed so as to be effective to also move the armature in the initial stage of its return flight. Ordinarily the breaker point spring is located between the base of plunger 18 and the upper face 85 of ledge 26 so that it is not in any sense effective to move the armature toward its poles,—having on the contrary the directly opposite effect. As shown in Fig. 5, I have 90 located the breaker point spring, designated 28, between the flange 27 and base B, or any other suitable and underlying abutment. By so doing, the spring 28 is enabled to supply the lifting force to move armature 21, by 95 means of the interengagement of flange 27 and ledge 26, in the initial stage of its return flight,—carrying it sufficiently close to the magnetic poles, afforded by the lower 100 ends of cores 8, so that the armature can be drawn into its upper position by the force of magnetic attraction. The spring 28 lifts the armature until the breaker points 16 and 19 engage and the e points cooperate as 105 positive stops to limit the lifting action of the spring on the armature. Since the final stage of the return flight of the armature is effected by magnetic attraction, the ledge 26 is carried above the flange 27. Thus, the 110 armature in its movement away from its poles can move freely, so far as opposition from spring 28 is concerned, until ledge 26 engages flange 27 to effect a separation of the breaker points. In other words, the 115 armature, during that part of its downward flight which is effective in the production of a spark from the magneto, is unopposed by the action of spring 28. After the breaker points open and as the armature continues to move downwardly, the spring 28 is compressed and acts in the usual way to cushion 120 and yieldingly arrest the armature.

125 The armature may be moved away from its poles by any suitable mechanism and various mechanisms will readily occur to those skilled in the art. The important con- 130

sideration is that the driving mechanism, whatsoever its character may be, is unopposed at a time when it is intended to move the armature as quickly as possible to produce a spark. Naturally, the invention is of greatest importance where a spring drive mechanism is employed to move the armature away from its poles but it nevertheless is useful where an inelastic transmission of force is used for moving the armature away from its poles for a reduction in opposing forces means a reduction in power required to effect such movement of the armature.

In order to illustrate both the above conditions, I have shown a known type of driving mechanism by which elastic or inelastic drive may be effected and which embodies provisions for shifting from one form of drive to the other. Referring to Figs. 2, 3, and 4, the shaft 25, to which the armature is fixed, has also fixed thereto a lever 30, to the free end of which a stud 31 is fixed. Slidable on shaft 25 is a sleeve 32 (Fig. 3) having a clutch groove 33 to receive a shifter arm 34 (Fig. 5) which may be manually moved by a lever 35 from the position shown in Fig. 2 to that shown in Fig. 3 or vice versa. Mounted side by side and for free turning movement on sleeve 32 are two arms 36 and 37 (Fig. 3). The upper arm 36 (Figs. 3 and 4) carries a right-angularly turned lug 38 which underlies the lower arm 37 and the latter carries a similar lug 39 (Fig. 4) which overlies the upper arm. These lugs 38 and 39 limit the degree to which arms 36 and 37 may be swung apart and a drive spring 40 interposed between the free ends of the arms tends to move the arms apart to the extent permitted by lugs 38 and 39. The spring 40 encompasses two lugs 41 (Fig. 4), one on each of the levers 36 and 37, and these lugs, which are normally held separated by spring 40, are adapted to be engaged by moving the levers toward one another. The upper lever 36 has a lug 42 which is engaged by a roll 43 mounted on a crank pin 44, carried by the drive shaft 45 which is rotatably mounted in frame A near one end thereof. Thus, lever 36 may be periodically depressed. The movement of lever 36 may be directly communicated to lever 30 by shifting sleeve 32 so that the lug 42 overlies the lever 30 as shown in Fig. 3. In this case an inelastic transmission of force is transmitted from the drive shaft 45 to the armature.

When sleeve 32 is shifted into the position shown in Fig. 2, the lug 42 no longer overlies lever 30. The lever 37, however, has a lug 46 which rests on the stud 31 carried by lever 30. Consequently, a depression of lever 36 will compress spring 40 against lever 37 which is held stationary by stud 31. The stressing of spring 40 continues until the lugs 41 are brought into engagement but

even then spring 40 has not been stressed sufficiently to enable it to move armature 21 away from its poles. The magnetic hold on armature 21 must first be broken and this is effected by an inelastic transmission from the drive shaft 45 through lever 36, the engaged lugs 41, lever 37, stud 31, lever 30, and shaft 25 to the armature. Immediately after the armature has been thus pried off its poles and as soon as even the slightest air gap is created between the same, the force of magnetic attraction on the armature is diminished to such an extent that the stressed drive spring 40 is enabled to move the armature. In the downward movement of the armature the opposition due to magnetic attraction rapidly diminishes and the expanding spring is thus effective to move the armature at accelerated speed and at a speed entirely independent of engine speed. At the optimum point in the downward flight of the armature the breaker points open and a spark is produced in the usual and known manner.

It will, therefore, be appreciated that it is important to reduce, so far as possible, the forces which oppose the downward movement of the armature up to the time when such movement is effective in the production of an E. M. F. from the magneto. By this invention the armature return spring is positively prevented from opposing the armature movement at the stated time and the only opposition from the spring comes in the final stage of the downward flight of the armature after the spark has been produced. Accordingly, such opposition does not matter.

It is not essential for all purposes that the return spring be the same spring which tends to close the breaker points. The same result can readily be effected by another spring leaving the breaker points to be operated in exactly the same way as heretofore. The invention, therefore, in its broadest aspect, is independent of the interrupter mechanism. However, it is desirable and preferred to utilize the breaker point spring as an armature return spring and to utilize the breaker points as stops to limit the action of the spring on the armature. There is, by so doing, the advantage of reduction in the number of parts by making one part perform two functions. There is also the advantage of securing perfect coordination in a very simple way for the breaker points themselves prevent opposition of the return spring on the armature until they open. The desired result is thus certain to occur at the proper time without providing any special timing means.

The invention has been disclosed herein, in an embodiment at present preferred, for illustrative purposes but the scope of the invention is defined by the appended claims rather than by the foregoing description.

What I claim is:

1. In a magneto, of the type wherein an armature is moved toward and away from magnetic pole pieces, driving means for moving the armature away from its pole pieces, elastic means tending to move the armature sufficiently toward said pole pieces so that the remainder of the return stroke may be effected by magnetic attraction, and means for restraining said elastic means from opposing the movement of the armature during the initial stage of its flight away from said pole pieces.

2. In a magneto, of the type wherein an armature moves into and out of contact with magnetic pole pieces to which it is normally held by magnetic attraction, mechanism for moving the armature away from its pole pieces including means effective by a non-elastic transmission to break the magnetic hold on the armature and previously stressed elastic means to move the armature after such hold has been broken, elastic means tending to move the armature toward its pole pieces, and means for limiting the action of the last named means on the armature so that it moves the armature only part way toward said pole pieces but sufficiently close thereto to enable the armature to be drawn into contact with its pole pieces by magnetic attraction.

3. In a magneto, of the type wherein an armature is moved toward and away from magnetic pole pieces, driving means for moving the armature away from said pole pieces, an interrupter mechanism associated with the magneto and comprising cooperating and relatively movable breaker points, and elastic means for the combined purposes of engaging said breaker points and of moving the armature toward its pole pieces and sufficiently close thereto to enable the remainder of the return movement of the armature to be completed by magnetic attraction.

4. In a magneto, of the type wherein an armature is moved toward and away from magnetic pole pieces to vary the reluctance of a magnetic circuit and a generating and a choke winding is associated with said magnetic circuit, the choke winding being ar-

ranged in an electric circuit which can be opened and closed, cooperating and relatively movable breaker points for opening and closing said electrical circuit, driving means for moving the armature away from its pole pieces, means for separating said breaker points at an intermediate point in the flight of the armature away from its pole pieces and elastic means tending to engage said breaker points and tending also to move said armature toward its pole pieces until restrained therefrom by the engagement of the breaker points, whereby the armature in its initial flight is unopposed by said elastic means up to the time when said breaker points separate.

5. In a magneto, of the type wherein an armature is moved toward and away from magnetic pole pieces, an interrupter comprising cooperating and relatively movable breaker points, driving means for moving the armature away from its pole pieces, an abutment movable with the armature and an abutment movable with one of the breaker points, said abutment engaging at an intermediate point in the flight of the armature away from its pole pieces to separate said breaker points, and elastic means tending to hold said breaker points in engagement and acting also to move the armature toward its pole pieces through the intermediary of said breaker point abutment.

6. In a magneto, of the type wherein an armature is moved into and out of contact with magnetic poles, driving means for moving the armature away from its poles, an abutment movable with the armature, a second abutment, resilient means acting on the second abutment and tending to engage it with the first abutment for the purpose of moving the armature toward its poles, and a stop to limit the movement of the second abutment by said resilient means and arranged so that the armature is moved only part way toward its poles by said resilient means but sufficiently close to said poles so that the armature may be drawn thereto by magnetic attraction.

In testimony whereof I have affixed my signature.

TERRENCE G. LOUIS.
